UNITED STATES PATENT OFFICE.

JOHN DRAGUN, OF WILKES-BARRE, PENNSYLVANIA.

CONVERTIBLE TONGS OR PLIERS.

1,174,132.

Specification of Letters Patent.

Patented Mar. 7, 1916.

Application filed January 5, 1916. Serial No. 70,466.

To all whom it may concern:

Be it known that I, JOHN DRAGUN, a subject of the Emperor of Austria-Hungary, residing at Wilkes-Barre, in the county of Luzerne and State of Pennsylvania, have invented certain new and useful Improvements in Convertible Tongs or Pliers, of which the following is a specification.

This invention relates to certain new and useful improvements in convertible tongs or pliers.

The primary object of this invention is the provision of a plier or tong structure having a readily convertible jaw arrangement for operating upon either plane or curved surfaces.

A further object of the invention is the provision of a pair of tongs having shiftable jaw members presenting different forms of engaging surfaces at the different angles of adjustment thereof for accommodating the device for employment with work having surfaces of different forms.

A still further object is the provision of a pair of tongs that is easy and inexpensive to manufacture but which is highly efficient in its employment either as a pipe tongs for engaging curved or cylindrical objects or as a pair of pliers in its usual uses such as grasping flat-sided objects.

With these general objects in view and others that will appear as the nature of the invention is better understood, the same consists in the novel combination and arrangement of parts hereinafter more fully described, illustrated in the accompanying drawings, and pointed out in the appended claims.

In the drawing forming a part of this application and in which like designating characters refer to corresponding parts throughout the several views:—Figure 1 is a perspective view of the device arranged as a pair of pliers. Fig. 2 is a front elevation of the same positioned as pipe tongs in engagement with the pipe, the handle members being broken away and the jaws illustrated in dotted lines shifted to their plier positions, and Fig. 3 is a side view thereof.

Referring more in detail to the drawings, two handles 10 and 11 are arranged pivotally connected together by means of a pivot pin 12 in substantially the usual manner, the said handles having a bifurcated

jaw shank 13 and 14 respectively positioned opposite each other and adapted to be brought into substantial contact with each other when the handles are closed together. The said jaw shanks are bifurcated having 60 their opposite sides 15 perforated for receiving pivot pins 16 upon which convertible jaws 17 are swingingly mounted. These jaws 17 are substantially right-angular in form, and each has a leg member 18 that 65 is pivotally mounted upon the afore-mentioned pins 16 between the shank sides 15 substantially midway of the length of the said legs 18 and the legs 18 are provided at one end with inclined faces 19 upon one 70 side and with serrated engaging faces 20 upon the opposite sides. A projecting foot 21 is provided upon each of the legs 18 at the end thereof opposite its inclined end 19. The feet 21 are provided with trans- 75 verse grooved faces 22 adjacent the flat sides 23 of the legs 18. The jaws 17 are adapted to be swung upon the pins 16 for arranging the face 20 oppositely positioned for employing the device as pliers as illus- 80 trated in Fig. 1 of the drawings, and at which time the shoulders 24 of the feet 21 engage the adjacent sides of the mounting shank for preventing swinging movement of the jaws. The jaws 17 may be swung 85 to their positions illustrated in Fig. 2 when desired for engagement with a curved surface such as the pipe 25. In this arrangement of the jaws, the inclined faces 19 are oppositely positioned and may be swung 90 into the inner end recesses 26, of the shanks when desired. In this position of the jaws 17, the same will seat with their inclined ends inwardly, thus clamping the pipe 25 between the grooved faces 22 of the feet 95 21 and the faces 23 of the legs 18. The tapered ends 27 of the legs 18 engage each other as shown in Fig. 2 of the drawings and act as levers with the pins 16 as fulcrums thereby forcing the feet and leg sur- 100 faces in firm engagement with the pipe. A serviceable and inexpensive tool is thus arranged which may be employed either as a pliers upon plane surfaces or as a pipe tongs in connection with pipes or cylindri- 105 cal work.

While the form of the invention herein shown and described is what is believed to be the preferred embodiment thereof, it is nevertheless to be understood that minor 110

changes may be made therein without departing from the spirit and scope of the invention as claimed.

What I claim as new is:—

- 5 1. A device of the class described comprising handles pivotally connected together and provided with extended bifurcated jaw shanks, having inwardly arranged sockets opening between the said shanks, pivot pins connecting the bifurcations of the said shanks, substantially right-angular shaped jaws pivotally mounted upon the said pins and comprising leg portions tapered at one end with oblique faces at one side and rough surface-engaging faces upon the opposite 30 side thereof and angularly-projecting feet at the opposite ends of the said legs having shank-engaging side shoulders and grooved faces adjacent the said legs, the said tapered ends of the jaws being received within the 35 said sockets when the jaws are arranged for gripping curved surfaces and with the feet of the jaws in substantial alinement with the handles.
- 10 2. A device of the class described comprising handles pivotally connected together

and having extended bifurcated jaw shanks, provided with inwardly arranged sockets opening between the said shanks, pivot pins connecting the bifurcations of the said shanks, substantially right-angular shaped jaws pivotally mounted upon the said pins and comprising leg portions tapered at one end with oblique faces at one side and rough surface-engaging faces upon the opposite 30 side thereof and angularly-projecting feet at the opposite ends of the said legs having shank-engaging side shoulders and grooved faces adjacent the said legs, the said tapered ends of the jaws being received within the 35 said sockets when the jaws are arranged for gripping curved surfaces and with the feet of the jaws in substantial alinement with the handles.

In testimony whereof I affix my signature.

JOHN DRAGUN.
